UNITED STATES PATENT OFFICE.

CLIFTON REEVES, OF TRENTON, NEW JERSEY.

STEAM-ENGINE CONSTRUCTION.

1,337,024.

Specification of Letters Patent. Patented Apr. 13, 1920.

Application filed March 23, 1916. Serial No. 86,066.

To all whom it may concern:

Be it known that I, CLIFTON REEVES, of Trenton, in the county of Mercer, and in the State of New Jersey, have invented a certain 5 new and useful Improvement in Steam-Engine Construction, and do hereby declare that the following is a full, clear, and exact description thereof.

My invention relates particularly to engines provided with devices for permitting the flow of steam in general in one direction, and which are known under the term "uni-flow engines."

The object of my invention is to provide a 15 valve mechanism for engines of this type, which is provided with an auxiliary port connection with the engine cylinder, and which is operated to remove the compression during the return stroke of the piston when, 20 for any reason, there is a back pressure in the exhaust from the engine, as, for example, when the condenser is not operating or is only partially operative, or when there 25 is a back pressure due to a heating system supplied with the exhaust from the engine.

A further object of my invention is to provide an apparatus of the above character, in which the valve controlling the auxiliary port is automatically shifted to open or 30 closed position, according to the presence or absence of such back pressure and without shocks.

A further object of my invention is to provide such an apparatus which may be 35 adjusted at will according to the conditions under which the engine is to operate.

While my invention is capable of embodiment in many different forms, for the purpose of illustration I have shown only one 40 form thereof in the accompanying drawings, in which—

Figure 1 is a vertical longitudinal section of a portion of an engine, showing the same equipped with my invention;

Fig. 2 is a side elevation of the same, partly in section.

In the drawings I have shown a suitable base 1, having located therein a pair of cylinders 2 and 2^a. The cylinders 2 and 2^a 50 and the parts connected thereto are constructed alike and I shall, therefore, only describe in detail one of said cylinders.

The cylinder 2 has a plurality of exhaust ports 3 which communicate with an annular chamber 4 leading to an exhaust pipe 5. On 55 the top of the cylinder 2 there is a head 6

having an inlet port 7 for steam and a chamber 8 for superheated steam so as to maintain the head at a high temperature. A piston 9 moves in the cylinder 2, the same being connected by a piston rod 10 to a crank 11 on a crank shaft 12 supported in the base 1. At the side of the cylinder 2 there is a port 13 connected by a passageway 14 located in a valve casing 15, having a valve 16 60 therein of the Corliss type, but of special design to suit the requirements. This valve 16 has a recess 17 for bringing the passageway 14 into communication with an exhaust port 18 located in the valve casing 15. Said valve 16 also has a similar recess 19 which is arranged to bring the exhaust port 18 into communication with a passageway 20 leading to the cylinder 2^a. On the end of the valve 16 there is a lever arm 21 which is connected by a ball joint 22 to an arm 23 having its lower end carried by a sliding block 24 65 adapted to move in a slot 25 in a lever 26, having a fixed pivot 27 on a bracket 28 attached to the base 1. This lever 26 has, furthermore, at one end thereof, a screw 29 for limiting the movement of the block 24 in the slot 25. Said arm 23 is pivotally connected by a piston rod 30 to a piston 31 in a cylinder 32 connected by a pipe 33 to the exhaust. 70 Connected to the exhaust there may be provided a condenser of the usual type, or a heating system, or both. The piston rod 30 has a slot 34 to receive a pin 35 on a lever 36 connected to a shaft 37 carried by the 75 bracket 28. On the shaft 37 there is fixed a weighted arm 38 which insures forward movement of piston rod 30 when the desired pressure (or vacuum) is not maintained in the exhaust. Pivotally connected to the 80 bracket 28 there is an eccentric rod 39 operating on an eccentric 40, carried on the 85 crank shaft 12.

In the operation of my invention, steam is admitted to the cylinders 2 and 2^a, thus causing the pistons therein to move in their cylinders. These pistons move in opposite directions simultaneously in the cylinders. The piston 9, for example, is moved downwardly by the steam until it uncovers the 100 ports 3, whereupon the steam is exhausted through the pipe 5. When the piston 9 has reached the lowermost portion of its path of movement it begins to ascend and then covers the ports 3. As soon as this takes place, 105 in case the condenser has been operating properly, the valve 16 will remain in its mid-

idle or closed position. That is to say, when the valve mechanism is in this position the block 24 will overlie the pivot 27 so as not to move the arm 23. In case, however, there is 5 for any reason undue pressure in the cylinder, piston 31 will be advanced in cylinder 32, by reason of the communication between such cylinder and the exhaust through pipe 33, and the consequent movement of piston 10 rod 30 will throw arm 23 to a position more remote from pivot 27. The reciprocation of the eccentric rod 39 will then move the valve 15 16 through the agency of the arm 21, thus exhausting some of the steam from the rear of the piston 9. The same will, of course, take place in the other cylinder 2^a when similar conditions are present. Whenever desired, the range of movement of the block 24 in the slot 25 may be limited by the position 20 of the screw 29.

While I have described my invention above in detail, I wish it to be understood that many changes may be made therein without departing from the spirit of my invention.

25 I claim:

1. In combination, a pair of cylinders having inlet and exhaust ports, and auxiliary exhaust ports located between the same, a

two-way valve connected to said latter exhaust ports, and means controlled by the 30 back pressure on the cylinders for actuating said valve to relieve alternately the compression in said cylinders.

2. In combination, a pair of cylinders having inlet and exhaust ports, and auxiliary 35 exhaust ports located between the same, a two-way valve connected to said latter exhaust ports, an operating arm for said valve, and means for controlling the range of movement of said arm responsive to changes 40 in the back pressure on the cylinders.

3. In combination, a pair of cylinders having inlet and exhaust ports, and auxiliary exhaust ports located between the same, a two-way valve connected to said latter exhaust 45 ports, an operating arm for said valve, a slotted link actuated from the crank shaft engaging said arm, and an exhaust controlled piston connected to said arm.

In testimony that I claim the foregoing I 50 have hereunto set my hand.

CLIFTON REEVES.
